UNITED STATES PATENT OFFICE.

JOSEPH HENRY FRYER, OF GALT, ONTARIO, CANADA.

APPARATUS FOR ANNEALING MALLEABLE-IRON CASTINGS.

1,150,512.

Specification of Letters Patent. Patented Aug. 17, 1915.

Application filed November 19, 1914. Serial No. 872,961.

To all whom it may concern:

Be it known that I, JOSEPH HENRY FRYER, of the town of Galt, in the county of Waterloo, in the Province of Ontario, Canada, have invented certain new and useful Improvements in Apparatus for Annealing Malleable-Iron Castings, of which the following is the specification.

My invention relates to improvements in apparatus for annealing malleable iron castings and the object of the invention is to devise means whereby the formation of scale on the parts annealed and the warping of such parts during annealing is prevented and it consists essentially of a series of open ended containers and intermediate hermetic closures for the open ends of the containers as hereinafter more particularly explained by the following specification.

20 Figure 1, is a perspective view showing a vertical series of containers and intermediate closures. Fig. 2, is a vertical section through Fig. 1. Fig. 3, is a plan section on line *x*—*y* Fig. 2.

25 In the drawings like letters of reference indicate corresponding parts in each figure.

1, 2 and 3 are a series of open ended containers.

4 is a base plate provided with a surrounding flange 5 extending upwardly therefrom around its outer edge. The lowermost container 1 rests on the base plate 4 so as to leave a small surrounding space between the outer face of the wall of the container and the inner face of the surrounding rib 5.

6 is a filling of clay or other suitable material inserted between the rib 5 and the lower edge of the container 1. 8 is a similar filling of clay inserted around the lower interior edge of the container upon the plate 4. By this means an air tight joint is formed between the lower edge of the container and the plate.

45 7 and 16 are plates inserted respectively between the containers 1 and 2 and 2 and 3. The plate 7 is provided with exterior upwardly and downwardly extending flanges 9 and 10 similar to the flange 5 hereinbefore described in connection with the plate 4.

11 is a downwardly extending flange extending from the plate 7 and designed to fit the upper end of the container 1.

12 and 13 are fillings of clay or other

suitable material inserted between the flange 5 and lower edge of the container 2 and the flange 10 and upper edge of the container 1.

14 is a similar filling of clay inserted against the interior lower edge of the plate 2 and resting on the plate 7. By this means an air tight joint is formed between the containers 1 and 2. The plate 7 is provided with a central orifice 15 for a purpose which will hereinafter appear.

16 is a plate similar to the plate 7 with the exception that it is a solid plate having no central orifice similar to the orifice 15. The plate 16 is inserted between the containers 2 and 3 and is provided with a corresponding clay filling to form an air tight joint.

17 is a cover plate designed to fit over the uppermost container. The cover plate 17 is provided with an interior depending flange 18 fitting within the container 3 and a depending flange 19 spaced slightly away from the outer face of the container 3. 20 is a clay filling inserted between the flange 19 and the wall of the container 3.

By means hitherto employed the open ended containers have been arranged in vertical tiers one above the other, the castings or other parts to be treated being inserted in the container and surrounded by suitable packing such as sand. It will be readily understood that when the castings are subjected to great heat and are softened thereby that they are liable to warp under pressure of the load of the filling and castings contained by the superimposed containers, the lower containers being subjected to great pressure than the upper containers. Furthermore air circulates through the joints between the containers and comes into contact with the surface of the castings producing a scaly surface which has to be removed by machining after the annealing process has been completed. This it will be readily seen involves a great deal of time and labor particularly in intricate small castings where interior angles have to be cleaned of this scale.

By arranging my containers as above described with intervening hermetic closures the action of the air on the closures is prevented and the necessity for the use of filling is obviated and consequently the castings do not become covered with scale and

there is less tendency for the castings to warp as the lower castings neither have to carry the load of the filling nor of the upper castings. By my arrangement the castings of each container are carried by the underlying dividing closure plate, such as the plate 16 inserted between the containers 2 and 3.

As before described I have provided a central opening 15 in the plate 7. This is for the purpose of forming the containers 1 and 2 into practically one container so as to allow of the insertion of a very long casting.

From this description it will be seen that I have devised a very simple device whereby the formation of scale on the surface of the casting is obviated and a consequent economy of time and labor produced in finishing the castings. Further warping of the

castings is prevented producing a much better result.

What I claim as my invention is.

An apparatus for annealing malleable iron castings comprising a plurality of open ended containers set one upon the other, a base plate on which the lowermost container rests, a suitable filling carried by the base plate and surrounding the lower edge of the container, a plate having a central orifice interposed between each of the containers, a suitable filling carried by the plate against the walls of the containers, and an hermetic closing plate for the top of the uppermost container, as and for the purpose specified.

JOSEPH HENRY FRYER.
